ROOFING ELEMENT

Albert C. Fischer, Chicago, Ill., assignor to The Philip Carey Manufacturing Company, a corporation of Ohio

Original application September 17, 1921, Serial No. 501,443. Divided and this application August 26, 1929. Serial No. 388,456

11 Claims. (Cl. 108—7)

The present invention relates to roofing elements which are adapted to be applied to a building structure for the purpose of providing an improved weatherproofing covering, and particularly pertains to roofing strips or slabs having oblique stepped sides in which the exposed stepped portions on one or both sides are separated by intervening recesses or the like to simulate individual shingles and give an ornamental 10 design to the roofing.

This application is a division of application Serial No. 501,443 filed September 17, 1921.

Heretofore roofing strips or slabs have been serrated at intervals on one edge to provide a 15 series of exposed tabs for simulating individual shingles, when the strips or slabs are laid horizontally in overlapping courses. Moreover, these horizontally laid strips or slabs have been arranged in the successive courses so that the tabs 20 of alternate courses break joints with the recessed portions between the tabs of the immediately underlying course. This manner of laying the strips in the courses gives a roof covering of irregular design, simulating individual 25 shingles, rather than a uniform ornamental design wherein the tabs and recesses are in vertical alignment.

For a better understanding of the invention, reference will be made to the accompanying 30 drawing, in which,

Fig. 1 is a plan view of a roofing strip embodying the present invention;

Figs. 2, 4, 6 and 8 are plan views of modified forms of roofing strips; and

Figs. 3, 5 and 7 are sections of roofing coverings composed of roofing strips such as are shown in respective Figs. 2, 4 and 6.

Referring now to the drawing, the novel and improved roofing product is shown in one form 40 in Fig. 1 wherein an oblique strip or slab 2 is cut from a sheet of prepared roofing with stepped edges 3 on the side to be exposed. The stepped portions on one or both sides are further set off from the body of the strip by recesses 4 which extend into the body preferably to a distance equal to the length of the exposed tab. The strips, thus formed are laid in successive 45 overlapping courses with the tabs 5 and recesses of each course in vertical alignment with the respective tabs and recesses of the other courses, thereby forming a roof covering of artistic and ornamental appearance as well as preventing any tendency of the tabs to curl. The recesses 50 co-operate to form continuous grooves which accentuate the division lines between the vertical

tab rows and give them the appearance of relatively thick elements such as tile. The thickness of the tab elements may be further accentuated by cutting the tab ends in arcuate form 6 (Figs 2 and 3).

In Fig. 4 the strip is formed of the same general construction as above described, but with the tab ends on one side of the strip converged to a point 7 to effect the roofing design illustrated in Fig. 5.

In Fig. 6 the tabs are of somewhat different configuration and those on one or both edges may be alternately arranged to vary the design of the roofing covering or uniformly arranged as in Fig. 8 and in the other described modifications.

While I have shown certain specific embodiments for carrying my invention into effect, it is apparent that various other designs may be produced without departing from the spirit of the invention.

I claim:

1. A roofing strip comprising an elongated body having a series of individual shingles arranged diagonally in offset relation to provide tabs on the weather exposed edge, and recesses provided in the body to separate the tabs.

2. A roofing strip comprising an elongated body having a series of individual shingles arranged diagonally in offset relation to provide tabs on the weather exposed edge, and means formed in the body of the strip to separate the tabs.

3. A roofing strip having a series of uniformly designed individual shingles arranged diagonally in offset relation to provide tabs on the weather exposed edge, and recesses provided in the body to separate the tabs.

4. A roofing strip having a series of uniformly designed individual shingles arranged diagonally in offset relation to provide tabs on the weather exposed edge, and means formed in the body of the strip to separate the tabs.

5. A roofing strip having a series of individual shingles arranged diagonally in offset relation to provide tabs on the weather exposed edge, and means formed in the body coextensive with the length of the tab exposure to separate the tabs.

6. A roof covering composed of strips laid diagonally in overlapping courses, each of the strips comprising individual shingles offset in stepped relation to provide tabs on the exposed edge, recesses formed in the strip between the tabs, and the tabs and recesses of successive courses being vertically aligned to provide an ornamental design.

7. A roof covering composed of strips laid diagonally in overlapping courses, each of the strips comprising individual shingles of uniform design offset in stepped relation to provide tabs on the exposed edge, recesses formed in the strip between the tabs, and the tabs and recesses of successive courses being vertically aligned to provide an ornamental design. 80
8. A roofing strip comprising an elongated body having a series of individual shingles arranged diagonally in off-set relation to provide tabs along opposite edges, and recesses formed in the body to further separate the tabs on one edge of the strip. 85
9. A roofing strip comprising an elongated body having a series of individual shingles arranged in off-set relation to provide tabs along opposite edges, and means formed on the body to further set off the tabs on one edge of the strip. 90
10. A roof covering composed of strips laid diagonally in overlapping courses, each of the strips comprising individual shingles offset in stepped relation to provide tabs on the exposed edge, division lines formed in the strips between the tabs, and the tabs and division lines of successive courses being vertically aligned to provide an ornamental design. 95
11. A roof covering of strips laid diagonally in overlapping courses, each of the strips comprising individual shingles of uniform design offset in stepped relation to provide tabs on the exposed edge, division lines formed in the strip between the tabs, and the tabs and division lines of successive courses being vertically aligned to provide an ornamental design. 100
